Robert Ham, of Troy, N.Y.
Assignor to
Smith Thaddeus & Co., of Albany, N.Y.
Letter Patent No. 1128. Dated Aug. 9, 1857.

The Schedule referred to in these Letters Patent and making part of the same.

To all whom it may concern:

Be it known that I, Robert Ham, of the City of Troy, in the County of Rensselaer, and State of New York, have invented or produced a new and original ornamental design for a Parlor Stove; and I do hereby declare that the following is a full and exact description of the same, reference being had to the annexed photographic drawings, making a part of this specification, in which

Fig. 1. is a front view, and

Fig. 2. an end view.

The same letters refer to like parts in both figures.

My ornamental design for a parlor Stove consists of two scale-work panels, a, a moulding, b, scroll-leaves, c, plume-leaves, d, e, and scale-work panels, f, on the front; scale-work panels g, a panel-piece composed of scroll-mouldings and leaves h, and a shield i, and mouldings j, on each end; and an ornamental top, K, and bottom I, the whole being so shaped and arranged together as to produce, the same appearance as is represented in the annexed photographic drawings.

What I claim as my invention or production and desire to secure by Letters Patent, is the above described ornamental design for a parlor-stove.
